EX
OP D 18,999

DESIGN.

C. WHEELER.
CURTAIN FABRIC.

Patented Apr. 2, 1889.

UNITED STATES PATENT OFFICE.

CANDACE WHEELER, OF NEW YORK, N. Y.

DESIGN FOR CURTAIN FABRIC.

SPECIFICATION forming part of Design No. 18,999, dated April 2, 1889.

Application filed February 20, 1889. Serial No. 300,627. Term of patent 7 years.

To all whom it may concern:

Be it known that I, CANDACE WHEELER, a citizen of the United States, residing at New York, in the county of New York and State of New York, have invented a certain new and original Design for Fabrics for Curtains, Draperies, &c.; and I do hereby declare the following to be a full, clear, and exact description of the same.

10 My design is intended for the ornamentation of fabrics intended more particularly for use in curtains, draperies, hangings, and the like.

It consists in the representation of groups 15 or bunches of plants of the genus *Narcissus*, comprising the flowers and leaves, each bunch being separate and connected to other bunches by ribbon. This design is continued indefinitely over the surface of the fabric, which may 20 be of any color or shade.

In the accompanying drawing, A represents the background formed by the fabric.

B represents the flowers and C the leaves of the *Narcissus*, and D are ribbons connecting the independent groups or bunches of 25 plant.

What I claim is—

The design for the ornamentation of curtain fabrics herein shown and described, the same consisting of the representation of 30 bunches of plants of the genus *Narcissus*, each bunch being separate and connected to other bunches by ribbons, all substantially as herein set forth.

In testimony whereof I have affixed my signature in presence of two witnesses.

CANDACE WHEELER.

Witnesses:

WM. TRUSLOW,
GRIFFIN B. DISBROW.
